UNITED STATES PATENT OFFICE.

AUGUST ENGSTRAND, ALFRED D. SUNDEEN, JACOB C. POPE, AND ROGER W. SAFFORD, OF MORA, MINNESOTA.

STOVE OR FURNACE.

SPECIFICATION forming part of Letters Patent No. 601,437, dated March 29, 1898.

Application filed March 10, 1897. Serial No. 626,819. (No model.)

To all whom it may concern:

Be it known that we, AUGUST ENGSTRAND, ALFRED D. SUNDEEN, JACOB C. POPE, and ROGER W. SAFFORD, citizens of the United States, residing at Mora, in the county of Kandabec and State of Minnesota, have invented a new and useful Stove and Furnace, of which the following is a specification.

This invention relates to certain improvements in stoves and furnaces for heating purposes, and has for its object to provide a device of this character of a simple and inexpensive nature having an improved and simplified arrangement of interior partitions and flues designed to increase the heating capacity of the stove or furnace.

The invention consists in a stove or furnace having a shell provided with a fire-pot, transverse diaphragms arranged across the shell, a hollow partition arranged centrally between the diaphragms and forming a gas-chamber within it, said partition being separated from the shell by a space or flue surrounding it and having at one end an opening affording communication between its inclosed chamber and said flue, said gas-chamber communicating with a smoke-outlet and the flue surrounding said partition being adapted for communication with the fire-pot at the side of the shell opposite to the opening in the partition which affords communication between the flue and the inclosed chamber.

The invention also consists in certain novel features of the construction, combination, and arrangement of the various parts of the improved stove or furnace whereby certain important advantages are attained and the device is made simpler, cheaper, and otherwise better adapted and more convenient for use, all as will be hereinafter fully set forth.

The novel features of the invention will be carefully defined in the claims.

In order that the invention may be the better understood, we have shown in the accompanying drawings one embodiment thereof, in which drawings—

Figure 1 is a perspective view showing a stove or furnace constructed in accordance with our invention, and Fig. 2 is a vertical section taken axially through the same. Fig. 3 is a transverse section taken through the improved stove or furnace in the plane indi-

cated by the line *a a* in Fig. 2. Fig. 4 is a transverse section taken through the improved stove or furnace in the plane indicated by the line *b b* in Fig. 2. Fig. 5 is a fragmentary view showing the construction of the valve or chamber employed for controlling the direct passage from the fire-pot to the smoke-outlet.

The stove or furnace is constructed with a base comprising an annular lower portion 1, having legs 1^a and a platform extending over said annular lower portion and provided with an upturned annular flange 2 surrounding it, the edge of said platform forming an annular flange 3, projecting beyond the edges of the ring 1, on which flange 3 rests the shell 4 of the stove, which may be of any desired form in cross-section, being herein shown as elliptical and provided at its top with a closed cover 5, from the under side of which depends a centrally-arranged heat-spreading cone 6, as clearly shown in Fig. 2.

The front wall of the shell 4 is provided in its upper part with an opening 7, serving as a charging-door, and this opening is adapted to be closed by a door 8, hinged at one side thereof and provided with a fastening device 9 of any preferred kind. The opening 7 leads into the fire-pot 10 of the stove, which is formed within a shell 11, located within the shell 4 and by preference of the same form in cross-section, but of less diameter than said shell, as clearly shown in the sectional view Fig. 3.

The fire-pot 10 is provided at its lower part with a grate extending across the shell 11 and serving to separate the fire-pot 10 from the ash-chamber 20, located in said shell 11 beneath it. As shown by Fig. 2, the grate comprises two parts 12 and 13, the part 12 being stationary and the part 13 being pivoted, as indicated at 14, to the under side of said part 12 at the rear portion of the grate. In order to support and guide the forward portion of the lower part 13 of the grate, we provide a guide-pin 15, depending from the under side of the upper part 12 of the grate, extending through a slot 16, formed in the lower portion of the grate. The lower end of the guide-pin 15 carries a wearing-plate 18, on which the part 13 of the grate rests and plays.

The lower part 13 of the grate is provided

at its forward edge with a depending handle 19, by means of which it may be operated; and the front wall of the shell 4 and the wall of the inner shell 11, adjacent thereto, are provided with openings forming a doorway leading into the ash-chamber 20 and affording access to the grate. The doorway is provided with a door 21, hinged at one side of the opening and provided with a register 23 to control the air supplied to the fire-pot 10 through the grate. The parts 12 and 13 of the grate are provided, respectively, with series of apertures 12^a and 13^a, arranged concentrically with the pivot-pin 14 and adapted to be brought into and out of alignment with each other by the pivotal movement of said part 13 of the grate.

The inner shell 11 of the stove being of less diameter than the shell 4 and being arranged with its front wall adjacent to the front wall of said shell 4, a vertical flue 23 is formed surrounding the remaining portion of the shell 11, as shown in Fig. 3. The shell 11 is provided with a closed bottom 24, as seen in Fig. 2, and this bottom is extended to form a flange 24^a, projecting transversely across the lower end of the flue 23, but provided, as seen in Fig. 3, with three openings 25, located at the back part and at the opposite sides of the stove and adapted for the passage of the products of combustion passing down through the flue 23.

Between the bottom 24 of the inner shell 11 and the platform at the base of the stove is arranged a diaphragm 26, extending transversely and horizontally across the shell 4 and spaced apart both from the bottom 24 of the shell 11 and from the platform at the base of the stove. In the space between the diaphragm 26 and the bottom 24 of the shell 11 is arranged a partition 26^a, extending centrally in the shell 4 and serving to support the rear part of the shell 11, as will be readily understood. The spaces on opposite sides of the partition 26^a form flues 27, extending horizontally at opposite sides of the lower portion of the shell 4, which flues are adapted for communication by way of the openings 25 with the vertical flue 23.

The diaphragm 26 is provided with an opening 28 at the forward part of the shell, and through this opening the gases from the flues 27 pass downwardly into the space between the diaphragm 26 and the platform at the base of the stove, as indicated by the arrow in Fig. 2. In the space beneath the diaphragm 26 is arranged a hollow partition 30, located under the rear part of the shell 11, similarly to the partition 26^a above referred to, and the spaces on opposite sides of this partition 30 form horizontal flues 29, extending along opposite sides of the stove at the base thereof. The hollow of the partition 30 forms a chamber 31 to receive the gases passing through the flues 29 and to permit the entry of the gases into said chamber. The rear wall of

the partition is provided with an opening, as shown in Fig. 4. The platform at the base of the stove is provided with a central opening 32, leading into the chamber 31, as clearly shown in Figs. 2 and 4, and affording communication between said chamber and the smoke-flue of the stove, which is provided with a horizontal lower portion 34, extending under the platform of the base rearwardly from said opening 32 and communicating at the back of the stove with the vertical portion 35, which leads to a flange 36 for receiving the stovepipe. The front end of the horizontal portion 34 of this flue is open and is provided with a door 37, having a handle 38 and held in place by spring-clips 39 or other suitable devices.

As shown in Figs. 3 and 4, the smoke-flue 35 extends outside the shell 4 of the stove and is formed separately therefrom, having flanges at its opposite sides which are riveted or otherwise secured to the outer surface of said shell. The walls of the shell 4 and the smoke-flue 35 are provided near the top of said flue with an opening 40, adapted to be closed by a damper or valve 41, carried on the end of a slide-rod 42, movable transversely across the flue 35 and serving to permit the passage of the products of combustion directly from the fire-pot to the upper part of said smoke-flue.

In the operation of the improved stove or furnace it will be seen that when the fire is kindled in the fire-pot the draft-opening 40 may be opened, so as to increase the draft by affording direct communication to the fire-pot and the chimney, and after the fire is burning said draft will be closed, so as to cause the products of combustion to pass down by way of the flue 23, through the opening 25 in the flange 24^a, and into the flues 27 at opposite sides of the stove, whence the heated gases pass down and in the opposite direction through the flues 29, immediately beneath the flues 27, and enter the chamber 31 at the base of the stove. From this chamber the gases pass by way of the opening 32 down into the horizontal portion 34 of the smoke-flue and up through the vertical portion 35 thereof and escape to the chimney. In this way it will be seen that the heated gases from the fire-pot are caused to circulate back and forth through the flues at the lower portion of the stove, so that a considerable heat will be imparted to the walls of the flues and will be radiated therefrom, and it will be evident that, when desired, the flues at the lower portion of the stove may be provided with jacks, such as are commonly provided in furnaces for heating purposes. The arrangement of the horizontal portion 34 of the smoke-flue with its open end permits said flue to be thoroughly cleaned, when desired, in order that the draft through the same shall not be impaired, and for the same reason the front wall of the shell 4 is provided

at its lower part with a door 43, as shown in Fig. 2, to permit access to the horizontal flues 27 and 29.

From the above description it will be seen that our improved stove or furnace is of an exceedingly simple and inexpensive nature and is especially well adapted for use for heating purposes, and it will be seen that the invention is susceptible of certain modifications without material departure from its principles and spirit, and for this reason we do not wish to be understood as limiting ourselves to the precise form and arrangement of the parts herein set forth.

Having thus described our invention, what we claim is—

1. A stove or furnace having a shell provided with a fire-pot and smoke-outlet, transverse diaphragms arranged across the shell, a hollow partition arranged centrally between the diaphragms and forming a gas-chamber within it, said partition being surrounded by a flue separating it from the shell and having at one end an opening affording communication between its inclosed chamber and said flue, said chamber being adapted for communication with the smoke-outlet and the flue surrounding the partition being adapted for communication with the fire-pot at the side of the shell opposite to the opening in the partition which affords communication between the flue and the inclosed chamber, substantially as set forth.

2. In a stove or furnace, the combination of an outer shell, an inner, fire-box shell, closed at its bottom by a diaphragm, and arranged within said outer shell to form therewith, and in connection with said diaphragm, a downdraft-flue, two horizontal flues situated between said diaphragm and the stove-bottom, and connected one to the other, to form a return circuitous course for the heat and products of combustion below the fire-pot, one of said horizontal flues communicating directly with the downdraft-flue, and a smoke-outlet connected to the other horizontal flue, as and for the purposes described.

3. In a stove or furnace, the combination of an outer shell, an inner fire-pot shell closed at its bottom by a diaphragm and situated within the outer shell to form in connection therewith, and with said diaphragm, a vertical downdraft-flue, a grate within the fire-pot shell and above the diaphragm thereof, another diaphragm 26 situated between the stove-bottom and the fire-pot diaphragm and forming, above and below said diaphragm 26, horizontal return-flues situated in different horizontal planes, and partitioned to conduct the heat or products of combustion back and forth horizontally beneath the fire-pot, the upper horizontal flue communicating directly with the downdraft-flue between said shells, and a smoke-outlet extending beneath the stove-bottom and connected directly with the lower horizontal flue, as and for the purposes described.

4. In a stove or furnace, the combination of two shells arranged one within and of less cross-sectional area than the other, the walls of the shells being spaced apart to form a flue between them, and the inner shell being provided with a closed bottom which projects beyond the inner shell and forms a flange extending across the flue around the inner shell, said flange having perforations, a grate dividing the inner shell into a fire-pot and an ash-chamber, the shells having openings leading into the fire-pot and ash-chamber, a diaphragm extending across the outer shell beneath the ash-chamber and forming between it and the bottom of the inner shell a space, a partition dividing said space into two horizontal flues, each communicating at one end with the flue surrounding the inner shell and having its other end adapted for communication with a smoke-outlet, substantially as set forth.

5. In a stove or furnace, the combination of two shells arranged one within the other and separated by a downwardly-extending flue, the inner shell having a grate and forming a fire-pot, diaphragms below the fire-pot, a hollow partition arranged centrally between the diaphragms and forming a gas-chamber within it, said partition being surrounded by a flue and having at one end an opening affording communication between its inclosed chamber and said flue, said flue being adapted for communication with the downwardly-extending flue between the shells, and a smoke-flue extending vertically of the shell and having its lower end extending horizontally beneath and adapted for communication with the gas-chamber in said hollow partition, substantially as set forth.

6. In a stove or furnace, the combination with an outer shell, and an inner fire-pot shell, closed at its bottom by a diaphragm and forming a downdraft-flue, of the diaphragm 26 situated between the fire-pot diaphragm and the stove-bottom, a partition between the fire-pot diaphragm and the diaphragm 26, to form a horizontal flue that connects directly with the downdraft-flue, another partition situated between the diaphragm 26 and the stove-bottom and recurved upon itself to form another horizontal flue which extends between, and outside of, said partition so as to receive heat and products of combustion from the first-named horizontal flue and to discharge the same to an outlet 32, and a smoke-flue to which the outlet 32 discharges, as and for the purpose described.

In testimony that we claim the foregoing as our own we have hereto affixed our signatures in the presence of two witnesses.

AUGUST ENGSTRAND.

ALFRED D. SUNDEEN.

JACOB C. POPE.

ROGER W. SAFFORD.
